FLAGPOLE HOLDER

Robert C. Faulhaber, 209 Princeton Ave., Stratford, N.J.

Filed May 13, 1964, Ser. No. 79,967

Term of patent 14 years

(Cl. D29—17)

I claim:

The ornamental design for a flagpole holder, substantially as shown.
